(57) **CLAIM**

The ornamental design for a toilet lifter, as shown and described.

DESCRIPTION

FIG. 1 is a perspective view of a toilet lifter showing my new design;

FIG. 2 is an enlarged bottom perspective view thereof;

FIG. 3 is a front elevational view thereof;

FIG. 4 is a top plan view of FIG. 2 thereof; and,

FIG. 5 is a side elevational view thereof, the opposite side is a mirror image.

The broken lines form no part of the claimed design.
